[57] CLAIM

The ornamental design for a container for lingerie or the like, as shown and described.

DESCRIPTION

FIG. 1 is a front elevational view of a container for lingerie or the like showing my new design;

FIG. 2 is a side elevational view;

FIG. 3 is a side elevational view with the lid in an open position;

FIG. 4 is a top plan view;

FIG. 5 is a rear elevational view; and

FIG. 6 is a front perspective view with the lid in an open position.

The broken lines in FIG. 5 represent score lines.
